UNITED STATES PATENT OFFICE.

JOSEPH W. NORCROSS, OF LOCKPORT, NEW YORK.

ROWLOCK.

SPECIFICATION forming part of Letters Patent No. 243,294, dated June 21, 1881.

Application filed April 25, 1881. (No model.)

To all whom it may concern:

Be it known that I, JOSEPH W. NORCROSS, a citizen of the United States, residing at Lockport, in the county of Niagara and State of New York, have invented new and useful Improvements in Rowlocks, of which the following is a specification.

This invention consists in a bracket having in its under side a guide-recess, within which is confined a longitudinally-sliding bolt having a bifurcated inner end, which embraces a circular groove in the lower end of the thole or lug pin of the rowlock; also, in the combination of the thole or lug pin arms extending laterally from the thole or lug pin, a swiveling support for the oar extending from the upper part of the thole-pin, and a cam-plate which is acted on by the laterally-extending arms.

This invention is illustrated in the accompanying drawings, in which Figure 1 represents a plan or top view. Fig. 2 is a side view. The remaining figures are details, which will be referred to as the description progresses.

Similar letters indicate corresponding parts. In the drawings, the letter A designates a gunwale of a boat, to the edge of which is firmly secured the bracket B, in which is formed the socket for the thole or lug pin C.

In the under surface of the bracket B is a recess which forms the guide for a bolt, D, the inner end of which (see Fig. 3) is bifurcated and engages with a circular groove, a, in the inner end of the thole or lug pin, so as to keep the same down in its socket, while it does not interfere with its revolving motion. When the bolt is drawn back the thole or lug pin can be unshipped. In the example shown in the drawings the bolt D is made in the form of a spring, which retains its position by frictional contact; but an ordinary bolt may be used which is subjected to the action of a spring.

On the top of the bracket B is secured a cam-plate, E, and from the thole or lug pin extend two arms, b b, which engage with the said cam-plate. When the oar trails or is turned inboard the arms b b drop into recesses c, Fig. 5, in the cam-plate, the edges or side walls of which are sufficiently steep to retain the oar in either of these positions; but if the oar is in position for use the arms b b drop into comparatively shal-

low recesses d, Figs. 1, 2, and 5, which do not interfere with the motions of the oar in rowing.

In the upper end of the thole or lug pin is formed an eye, e, which forms the bearing for the rounded end of a stem, f, projecting from the oar-support F, said end being fitted into the eye so that it can freely turn therein without being permitted to drop out.

The oar-support consists of a strap, g, which is firmly secured to the stem f, and bent as shown in Fig. 2, and with this strap is combined a cap, h, being connected to the same by a hinge-joint, so that it can be thrown back for the introduction of the oar. The outer end of the cap is provided with a projection, i, which, when the cap is turned down, engages with a slot, j, Fig. 4, in the outer end of the strap g, and in this position the cap is retained by a spring-stop, k, which is fitted into a socket (see Fig. 4) secured to the strap g. When this stop is depressed the cap h can be swung open and the oar can be taken out of or introduced into its support. The spring-stop is depressed by means of a finger-piece, l, secured to its lower end.

The pole P of the oar is round to fit the support F, and on said pole are firmly secured two rings or stops, m, at a suitable distance apart, so that the oar can turn and also slide in its support a sufficient distance for its convenient operation, while said ring-stops prevent the oar, from sliding through its support beyond the required limits.

Heretofore the thole-pin of a rowlock has been provided at its lower end with a circular recess engaged by the square end of a pivoted swinging spring-latch, but such does not constitute my invention, and is not claimed by me.

In my invention I employ a longitudinally-sliding bolt, arranged within and guided by a longitudinal recess in the bracket, and the inner end of the bolt is bifurcated, so as to embrace both sides of the grooved thole-pin, thereby providing a very secure but simple retaining device.

What I claim as new, and desire to secure by Letters Patent, is—

1. In a rowlock, a bracket, B, having in its under portion a guide-recess, in which is confined a longitudinally-sliding bolt; D, having

a bifurcated inner end, as described, in combination with the thole or lug pin C, having at its lower end the circular groove, *a*, which is embraced by the bifurcated end of the slide-bolt, substantially as described.

2. The combination, substantially as hereinbefore described, of the thole or lug pin, arms extending laterally from the thole or lug pin, a swiveling support for the oar extending from the upper part of the thole or lug pin, and a

cam-plate, which is acted on by the laterally-extending arms.

In testimony whereof I have hereunto set my hand and seal in the presence of two subscribing witnesses.

JOSEPH W. NORCROSS. [L. S.]
